UNITED STATES PATENT OFFICE.

GEORGE ROAN AND HENRY HELMHOLZ, OF CHICAGO, ILLINOIS.

BLOW-OFF COCK.

1,131,422.

Specification of Letters Patent.

Patented Mar. 9, 1915.

Application filed June 13, 1914. Serial No. 845,969.

To all whom it may concern:

Be it known that we, GEORGE ROAN and HENRY HELMHOLZ, citizens of the United States, residing at Chicago, in the county of Cook and State of Illinois, have invented 5 certain new and useful Improvements in Blow-Off Cocks, of which the following is a specification.

Our invention relates to blow-off cocks 10 and has for its primary object the provision of an improved blow-off cock which shall have improved means of attachment to a steam boiler or like device.

With the above and other objects in view 15 this invention consists substantially in the combination, arrangement, and construction of parts, all as hereinafter described, shown in the accompanying drawings, which form a part of this specification and show the 20 preferred embodiment of our invention, and more specifically set forth in the subjoined claims.

In the drawings: Figure 1 is an elevation of a detachable portion of our invention. 25 Fig. 2 is a section of our invention showing it attached to the wall of a steam boiler which is also shown in section. Fig. 3 is a section of our invention taken on the line 3—3 of Fig. 2, and looking in the direction 30 indicated by the arrows. Fig. 4 is a section of our invention taken on the line 4—4 of Fig. 1 and looking in the direction indicated by the arrows. Fig. 5 is an inner end elevation of our invention showing it attached 35 to the wall of a boiler or like device. Fig. 6 is an elevation of the remainder of our invention from which the portion shown in Fig. 1 is detached, and illustrates in section a portion of the wall of a boiler or like device to which it is attached.

The ordinary railroad locomotive is provided adjacent the bottom of its boiler with a blow-off cock operable from the cab of the locomotive by means of which the engineer 45 periodically blows out sludge and other impurities from the boiler. It is a disadvantage that an ordinary blow-off cock when it is out of order cannot be removed for adjustment or repair while the boiler of the 50 locomotive is under steam pressure, it being necessary to put the locomotive out of commission by withdrawing its fires and removing the steam and water from its interior, before the ordinary blow-off cock can be 55 safely removed from its position in the boiler. By the use of our invention such a

disadvantage is obviated, for we provide a blow-off cock connected to the boiler through a hollow plug closable at its inner end, the blow-off cock being detachable from the 60 plug after the inner end of the plug has been closed.

Reference numeral 10 indicates the wall of a boiler which is apertured for engagement with a hollow plug 11. The inner end of the plug 11 is provided with a web 12 which is apertured as at 13 for the passage of fluid and is also provided as at 14 with a central round aperture for engagement with a bolt 15. A smooth machined surface is 65 formed by the web 12 and the inner end of the plug 11, and fitting closely against this surface is one similarly machined surface of a disk 16, which is provided with apertures 17 adapted at a certain position of the 70 disk to register with the apertures 13. The disk 16 is also provided with a central squared aperture 18 registering with the round aperture 14 of the web 12. The bolt 15 engages the apertures 14 and 18, being 75 rounded where it engages the aperture 14 and squared similarly to the aperture 18 for engagement therewith.

The inner end of the bolt 15 is threaded for engagement with a nut 19 to secure the 80 disk 16 upon the bolt. A stop 20 provided upon the bolt adjacent its outer end forms an abutment for one end of the spring member 21 the opposite end of which abuts against the outer surface of the web 12. By 85 this construction the disk 16 is held in constant engagement with the inner end of the plug 11 and the web 12 and by rotation of the bolt 15 the disk 16 may be oscillated to bring an imperforate portion of the disk 90 opposite the apertures 13 to close them or vice versa to cause the apertures 13 and 17 to register and permit the passage of fluid outwardly from the boiler. A half union 95 nut 22 of any well known construction encircles the outer end of the hollow plug 11, the plug being provided with the ordinary peripheral flange at its outer end for engagement with the nut. The outer end of the plug 11 is machined or ground to a 100 smooth surface and fitting closely thereto is the inner end of the blow-off cock 23 of our device, the outer periphery of the inner end of the blow-off cock 23 being threaded for engagement with the half union nut 22, by 105 which construction the blow-off cock and plug are firmly bound together.

The blow-off cock 23 is provided with the ordinary discharge nozzle indicated by reference numeral 24 and it is also provided with a central hollow sleeve 25. The outer end of the blow-off cock 23 is centrally bored to form with the hollow interior of the sleeve 25 a passage for engagement with a stem 26. The outer end 27 of the stem 26 protrudes beyond the outer end of the blow-off cock 23, and the inner end is formed into a disk 28 similar to the disk 16 but of such a diameter as to fit closely within the interior of the hollow plug 11. The stem 26 also fits closely within its passageway to prevent the escape of fluid. Apertures 29 similar to the apertures 13 and 17 are formed in the disk 28 and the disk is provided with a central squared hole for engagement with a squared extension 30 formed upon the outer end of the bolt 15. The squared extension upon the outer end of bolt 15 takes the form of a pyramid, the sides of which meet at the apex in preferably an acute angle. The central squared hole provided in the outer end of stem 26 is of a shape and size conforming to the pyramidal extension upon the outer end of bolt 15. To prevent a binding of the parts a slight space is left between the engaging surfaces of the pyramidal extension and the squared hole. The inner end of the blow-off cock 23 is provided with apertures 31 similar to the apertures 29 and adapted to register opposite those apertures in certain positions of the disk 28. Preferably there is provided between the inner end of the blow-off cock 23 and the adjacent surface of the disk a wear ring 32 provided with apertures 33 registering with the apertures 29 of the disk 28, the wear ring 32 and disk 29 being secured for rotation together within the hollow plug 11 by means of small pins 34 (see Fig. 3). The outer end 27 of the stem 26 is squared for engagement with a crank 35 which is held thereon by any suitable means such as the cotter pin 36. A washer 37 encircles the stem 26 and lies against the outer end of the blow-off cock 23, and disposed between this washer and the crank 35 is a compression spring member 38 which exerts an outward pressure upon the stem 26. This binds the disk 29 and the wear ring 32 closely to the inner end of the blow-off cock 23. The outer end of the blow-off cock 23 is provided with oppositely disposed sector-shaped extensions 39 which act as stops for a guard pin 40 transversely secured in the stem 26. The washer contacts upon its inner surface with the outer surfaces of the sector-shaped extensions 39. If, for any reason, an obstruction prevents the rotation of disk 16 in the closing of the blow-off cock, the form of connection between bolt 15 and stem 26 will permit the closing of the blow-off cock by disk 28 and wear ring 32, for the reason that the in-

clined surfaces of the pyramidal extension 30 will slide with relation to the engaging faces of the squared hole in the inner end of the stem 26, forcing the bolt inwardly against the pressure of spring member 21. 70

From the foregoing description it will be seen that by rotating the stem 26 the bolt 15 will be similarly actuated and both the disks 16 and 29 and the wear ring 32 will be turned in either direction, the amount of 75 turn being limited by contact of the guard pin 40 with the sector-shaped extensions 39. In Fig. 2 the parts are shown in open position for the free outward passage of the fluid from the boiler. The rotation of the stem 80 26 will bring imperforate portions of the disk 16 opposite the apertures 13, closing those apertures, and will also bring imperforate portions of the disk 29 and the wear ring 32 opposite the apertures 31, closing 85 those apertures also. If it is desired to remove the blow-off cock and its valve members 29 and 32 from the boiler for the purposes of adjustment or repair the stem is oscillated in the above mentioned manner to 90 close the inner end of the hollow plug 11, after which the half union nut 22 is rotated from its threaded engagement with the blow-off cock 23 and the blow-off cock withdrawn. 95

By means of the contact of smoothly machined or ground surfaces in our mechanism and the continual close contact provided for therebetween by means of the spring members 21 and 38 we obviate leakage through our device. By the use of the wear ring 32 which is detachable from the disk 28 we provide an easy means of taking up wear by substituting a new wear ring for a worn one. If it is desired to permit 100 fluid to pass outwardly from the boiler through the plug 11 when the blow-off cock is detached it is apparent that a wrench may be applied to the squared extension 30 of the bolt 15 and the disk 16 thereby rotated. 105

In the accompanying drawings and in the foregoing description is set forth the preferred embodiment of our invention, but it is obvious that one skilled in the art may 110 make modifications thereof without departing from the spirit of the invention.

We claim:

1. The combination of an apertured plug having a valve seat at one end thereof, a rotary valve fitted on said valve seat and adapted to coöperate therewith, a blow-off cock casing secured to the other end of said plug and provided with a valve seat opposite said plug, a rotary valve fitted to the seat on said casing and in axial alinement with the valve on said plug, means connecting said valves for simultaneous rotary movement, and adapted to permit the operation of the valve on said casing when 130

the valve on said plug is locked by an obstacle.

2. The combination of a plug, a valve co-operating with said plug, a blow-off casing 5 secured to said plug, a valve co-operating with said casing, and a connection between said valves causing the first mentioned valve to be operated upon operation of the second mentioned valve and adapted to permit the 10 operation of the latter when the first mentioned valve is locked by an obstruction.

3. The combination of a pressure chamber wall provided with an opening, a centrally bored plug secured in the opening and provided with a hollow outer end and a passage for fluid, a peripheral flange upon the outer end of the plug, a blow-off cock normally controlling the passage of fluid through the plug and provided with an exteriorly handled controlling stem having a squared aperture upon its inner end, a half union nut upon the plug co-operating with the flange and blow-off cock to removably secure the cock to the plug, a bolt mounted 25 for oscillation in the central bore of the plug and provided at its outer end with a squared extension engaging the squared aperture of the stem, and an apertured disk fixed upon the inner end of the bolt for oscillation 30 therewith for controlling the passage of fluid through the plug.

4. The combination of a pressure chamber wall provided with an opening, a blow-off cock normally controlling the opening and 35 detachable from the wall, an additional device for closing the opening, and a frictional spring pressed connection between the blow-off cock and the additional device whereby the blow-off cock may be caused when operated to operate the additional device simultaneously, but whereby obstruction of the additional device will not obstruct the operation of the blow-off cock.

5. The combination of an apertured plug having a valve seat at one end, a blow-off cock secured to the other end of said plug, 45 a disk valve fitted with said valve seat, a valve stem secured to said disk valve and extending into said plug into close proximity with said blow-off cock, and a clutch operatively connecting said valve stem with 50 said blow-off cock and being adapted to permit the operation of the blow-off cock when the disk valve is locked by an obstruction.

6. The combination of an apertured plug having a valve seat at one end thereof, a blow-off cock secured to the other end of the plug and having a valve seat opposite said plug, a rotary valve fitted to the valve seat on said casing, there being a recess pyramid in form in the side of said valve 60 on its side adjacent said plug, a manually operable valve stem secured to said valve and extending through said casing, a rotary valve fitted to the valve seat on said plug, a valve stem on the last mentioned valve extending into said plug and disposed in alignment with said manually operable valve stem, a spring on each of said valve stems resiliently holding its respective valve in operative condition, and a tongue pyramid 70 in form on the end of the second mentioned valve stem and disposed in said pyramid recess providing an operative connection between said valve and stems.

In testimony whereof we have signed our 75 names to this specification, in the presence of two subscribing witnesses, on this 11th day of June, A. D. 1914.
